Orange, N. J., a corporation of Delaware

Original application March 1, 1940, Serial No.
321,732. Divided and this application June 2,
1941, Serial No. 396,332

4 Claims. (Cl. 235—144)

The invention relates to registers, and it consists in the novel construction and combination of parts, as set forth in the appended claims.

The present application has been divided from application Serial No. 321,732, filed on March 1, 1940, by the present inventor and entitled "Registers."

The invention provides for the transmission of tens transfer movements concentrically with the numeral wheel axis through supporting frames which are provided between adjacent wheels, and for the support of said wheels on said axis by removable supports to facilitate the assembly and disassembly of said wheels, in a manner to avoid a binding action or excessive friction on the tens transfer mechanism due to unavoidable imperfections in the alignment of the axially mounted parts.

In the accompanying drawings, illustrating the invention,

Fig. 1 is a sectional view of the accumulator, taken on the line 1—1 of Fig. 2.

Fig. 2 shows in cross section a numeral wheel of the units order of the accumulator, the right hand supporting frame, an intermediate supporting frame, and the gear members related to the numeral wheel of the tens order.

Fig. 3 is a sectional view taken on line 3—3 of Fig. 2, showing the transfer aligner cam carried by each numeral wheel except the one of highest order.

Fig. 4 is a sectional view taken just inside the right end frame of the register carriage, with the parts in the position taken when the carriage is at the extreme left.

Fig. 5 is an elevation of the parts located in the right hand end of the carriage.

In Figs. 1 and 4 the intermediate supporting frames 151, which are shown in Fig. 2, are omitted for clearness.

In the drawings the invention is shown as it might be used in conjunction with the register mechanism of applicant's co-pending applications for United States patent, No. 176,156, filed November 24, 1937; No. 285,860, filed July 22, 1939; and No. 316,738, filed February 1, 1940, which is similar to the register mechanism of United States Patent No. 2,089,682, issued to George C. Chase on August 10, 1937. These disclosures illustrate the uses of the invention in connection with any wheel to wheel tens transfer type of register, as well as its more specific uses with a register of the crawl transfer type, with or without the feature of normal reading alignment which is shown in the applications and the patent.

Insofar as the parts shown in the present application correspond with parts shown in the issued patent, like part numbers will be used.

That patent and the co-pending applications show no zero setting mechanism for the accumulator, and make no provision for the return of the accumulator wheels to zero through the taking of a total as is commonly done if listing mechanism is provided.

United States Patent No. 1,932,013 issued to Loring P. Crosman on October 24, 1933, shows a listing machine having an accumulator of the crawl transfer type, but in order to restore the numeral wheels of said Crosman patent to zero, as in the total taking operation, it is essential that a successive zero setting action be provided, in which the numeral wheel of lowest order shall be cleared first, then the tens order, etc. There are various reasons for this requirement of successive zero setting of the numeral wheels of the Crosman patent, one of which would apply equally to a zero setting mechanism adapted to clear the accumulator of applicant's patent, or of the co-pending applications, through the numeral wheel actuating train.

If a simultaneously acting zero setting mechanism were applied to an accumulator constructed in accordance with the disclosures of Patent No. 2,089,682, or the co-pending applications, a cramping action would occur under certain conditions between the pinion 472, the sleeve of the eccentric hub 430, and the shaft 403 upon which these parts are mounted, as shown in Figs. 1 and 3 of that patent. This cramping action would occur in case the higher of two adjacent wheels is driven against its zero stop ahead of the lower order wheel, after which the member which moved said higher wheel to zero by rotating its pinion 472 reversely continues to press said wheel firmly against its zero stop, crowding the pinion hard against the sleeve, which is in turn pressed against shaft 403 during the time when the sleeve is to be rotated reversely by continued movement of the lower wheel. It has been observed in practice that this squeezing effect upon the sleeve may reach such proportions as to require positive instead of spring or frictionally impelled means for simultaneously resetting numeral wheels so constructed to zero. The present invention embodies improvements which eliminate this cramping action.

As shown in Figs. 1 and 4, digital values are transmitted to the numeral wheels 473 from the output gears 477 of the differential actuator mechanism, through the transmission train comprising the gears 480, 480', 482 and the pinion 472. This pinion is provided with a coupling member 471 (Figs. 2 and 4) which engages between spaced lugs 470' of a floating gear 470 to drive the latter in one to one ratio. In the units order of the accumulator, this gear is mounted on a fixed eccentric hub, while in each higher or-

der, it is mounted on an eccentric hub 430 which rotates with the numeral wheel of next lower order. The floating gear 470 meshes with internal teeth 473' of the numeral wheel 473, to transmit both direct digital and tens transfer values to that wheel, the first by rotary movement and the other by an orbital movement transmitted by hub 430. The gear 470 has nine-tenths as many teeth as the internal gear 473', thus providing for the tens transfer movement, as floating gear 470 is carried about its orbit.

A pin 487 is secured in each wheel, and passes through a slot formed in the aligner cam 485 related to each wheel excepting the one of highest order. A spring 488 is secured at one end to the pin, and at the other to the cam, to normally hold one end of the slot against the pin as shown in Fig. 3. This flexible connection between the numeral wheel and the aligner cam serves no new purpose in connection with the present invention, its purpose being described in United States Patent No. 2,089,682.

Each aligner lever 483 (Fig. 1) is provided with a lug 484 which may take its position against the aligner cam 485 of the next lower numeral wheel, under the influence of the spring 486. Aligner gear 482 (forming part of the above mentioned transmission train) is mounted on this lever, and meshes on its forward side with the pinion 472 of the numeral wheel of the same order, and on its rearward side with the gear 480'.

As the aligner lever 483 and the aligner gear 482 are lifted by cam 485 of a lower order wheel, a retractive or minus movement is imparted to the related numeral wheel, which is sufficient to counteract the crawl transfer effect which would otherwise be transmitted to that wheel from the wheel of next lower order.

A bail 489 (Figs. 4 and 5) is provided to lift all of the aligner levers during registering operations, permitting a free and uniform speed rotation of each numeral wheel. Normally, however, the lugs 484 of the several aligner levers rest against their related aligner cams.

The pin 487 which drives the aligner cam also engages an arm 146, formed on a sleeve of the eccentric hub 430, to drive the latter member in time with the next lower numeral wheel.

Since there are a greater number of numeral wheels in the register carriage 2 than output gears 477 in the base frame 1 of the machine, detents 147 (Fig. 4) are provided to prevent accidental displacement of the overhanging numeral wheels. Springs 148 impell the forwardly extending hooked arms of the detents between the teeth of gears 480, unless some means prevents this action. Plate 149 is secured to the stationary frame 1 of the machine, and holds all of the detents disengaged in orders in which the gears 480 are in mesh with the output gears 477. Recesses may be provided in the forward edge of this plate, to permit the dropping of the detents while the carriage is shifting, at which time the gears 480 may move from one to another of the gears 477.

The gear 480 should preferably be made wider than the gear 150 (to be hereinafter described) in order that the detent 147 may engage with the gear 480 and not interfere with the rotation of gear 150.

A supporting frame 151 (Fig. 2) is located between each two adjacent numeral wheels, and is provided with a cylindrical bearing, upon which the pinion 472 is mounted, while the sleeve of the

eccentric hub 430 which rotates with the wheel of next lower order is mounted within the bearing, so that any radial pressure from the pinion may not be transmitted to the sleeve. This eliminates the cramping action referred to above, and permits the combination of this mechanism with any zero setting means which simultaneously drive the numeral wheels against a zero stop, by yieldable means acting through the differential actuating transmission train. The intermediate supporting frames 151 are also advantageous in maintaining alignment of the accumulator elements of a four rules calculating machine, which is frequently provided with twenty or more numeral wheels.

The numeral wheels 473 and the aligner cams 485 are mounted for rotation concentric with the sleeves of the eccentric hubs 430 by means of a sectional shaft 403, the sections of which are in turn supported at each end within the sleeves of the eccentric hubs. By this arrangement a numeral wheel and its aligner cam may rotate upon their supporting shaft, or the shaft may rotate individually within the sleeves, which ever offers the least frictional resistance to rotation.

The shaft sections are held in their proper longitudinal position by means of adjustable screws 152, one in each end frame of the carriage, these screws being so adjusted as to permit slight endwise freedom between the shaft sections.

The aligner cams and the numeral wheels may be readily removed from the machine by removing screws 152 and the shaft sections, unhooking the springs 488 from the pins 487, and removing the cams, which provide the space necessary for the removal of the wheels. Any wheel and its related cam may be individually removed from the machine at will by the use of the well-known "follow through" shaft which is used to push out some but not all of the shaft sections, according to the position of the wheel which it is desired to remove, then retracting said shaft the distance of one numeral wheel space to free that wheel and its cam.

The use of a separate shaft section for each wheel, instead of a single shaft extending through the several wheels, eliminates any tendency to bind the sleeves of the eccentric hubs 430, resulting from imperfect alignment of the sleeve, or lack of straightness of the shaft.

Secondary actuator

The numeral wheels are normally driven by the output gears 477 of the differential actuator mechanism, but may alternatively be driven by the gears 150 which are mounted on the power shaft 153 (Fig. 4). Spring impelled plunger pins 154 carried by collars secured to the shaft engage each with one of a series of depressions formed in the adjacent gear, so that the gears will be driven in the rotation of the shaft unless held by some means, in which case the plunger pins will yield, permitting the shaft to complete its rotation. Such a construction is extensively used in the zero setting mechanism of calculating machines and is well known.

Each gear 150 is provided with a pin 155 which serves to limit the movement of the gear by contact with a tooth 156, secured upon the housing of the carriage. As shown in Fig. 4, the gear 150 is in its zero position.

As will be explained hereinafter, the gears 150 may serve for storing values, or indicating grand totals, as well as for a secondary actuator. Con-

sequently a numeral wheel 157 is secured to a gear 158 which is mounted on a shaft 159, and meshes with the gear 150. This numeral wheel may, if desired, be secured directly to the gear 150, and the gear 158 eliminated, or may even be eliminated altogether, since the gear 150 is of itself capable of indicating a grand total value as well as serving as a zero setting actuator for the accumulator 413, these grand total values being readable (or printable if listing mechanism is provided) by first transporting them back to the accumulator.

Selective meshing mechanism

A key 160 (Fig. 5) is provided for lifting the gear 480 from engagement with gear 477 and into engagement with the gear 150. Depression of this key rocks a lever 161 to which it is pivoted. This lever is pivotally mounted on a fixed stud 162 and is provided with a rearwardly extending arm which lifts a shaft 163. This shaft is mounted to rotate in arms 164 (Figs. 2 and 4), there being one of these arms at each end of the accumulator, with intermediate arms if necessary. These arms are pivoted at their forward ends upon the axis of the numeral wheels 473. Pinions 165 are secured to each end of shaft 163, and engage with fixed racks 166 so that the shaft is rotated as it is lifted, and maintained in a horizontal position, carrying the arms 164 with it. A rod 167 underlies the rearward ends of the arms, limiting their downward movement.

Shaft 481, upon which the gears 480 are free to rotate, is carried by the arms 164, forming therewith an oscillatory frame. The supporting frames 151 are not shown in Figs. 1 and 4, but slots are to be provided in these frames to permit the lifting of this shaft. Springs 168 tend to hold the gears 480 normally in mesh with gears 477.

The aligner levers 483 are also pivotally mounted on shaft 481, as seen in Fig. 1, so the aligner gears 482 which may stand in various positions, according to the position of the next lower numeral wheel (excepting the gear 482' of the units order which is mounted on the right hand arm 164) maintain substantially the same relative position when the gears 480 are lifted into mesh with gears 150, and may function as they should in registering or zero setting operations from either source of movement.

A spring impelled latch 169 snaps under the lifted shaft 481, holding the gears 480 in mesh with the gears 150, until this latch is manually or automatically released. The latch is pivoted on the shaft 153, and its upwardly extending end passes through a slot in the carriage housing, and is provided with a key button 170 which may be pressed manually to effect the release. A releasing lever 171 is pivoted on the latch, and provided with a lug 172 which is impelled by a spring 173 against the rearward edge of the latch, these two parts normally acting as one and the spring functioning to snap the latch beneath the shaft 481. Automatic means are provided to release the latch at the end of each clockwise rotation of shaft 153. Spring impelled plunger pin 174 is mounted near the right hand end of this shaft and serves to rotate cam 175 in a clockwise direction, but not in a counter-clockwise direction. A nose of follower lever 176 normally rests in a notch of the cam, and is positioned rearwardly during substantially the entire cycle of clockwise rotation of the cam. During its rearward movement, the lower end of

the lever encounters a lug 177 formed on the releasing lever 171, depressing the lever and passing to the rearward side of the lug, which resumes its previous position under the influence of the spring 173. When the nose of the lever falls back into the notch at the end of one revolution in a clockwise direction (under the influence of spring 178 as will be hereinafter described) the lower end of the lever encounters the lug 177, and the angle of the contacting faces is such that the lever 171 will not be depressed, but the latch 169 will be carried forward, allowing the shaft to resume its normal position with the gears 480 in mesh with the gears 477. In this action the latch 169 is carried forwardly somewhat more than is required to release the shaft 481, in order that the lug 177 which is moving in an arc about shaft 153 may escape from the lower end of lever 176, after which the spring 173 retracts the latch until it rests against the forward side of shaft 481, the lug 177 at the same time swinging beneath the lower end of lever 176 and coming to rest in the position shown in Fig. 5. The slot in the carriage housing through which the upper arm of the latch passes is long enough so that the arm may move a short distance rearwardly, and a greater distance forwardly from the position in which it is shown.

When the gears 480 are lifted into mesh with the gears 150 it is essential that the detents 147 which have previously been in engagement with the gears 480 which stood at the right or the left of the output gears 477 of the differential actuator mechanism shall be lifted. These detents are mounted on the shaft 163 which is lifted as previously described whenever key 160 is depressed, carrying rearwardly extending arms 179 of the detents against the rod 167, withdrawing any detents which may have previously engaged the gears. The numeral wheels 473 are now subject to the control of the gears 150.

Setting of the zero stop rocker frame

Whenever the shaft 153 and the cam 175 are rotated one revolution clockwise, rocking the lever 176 rearwardly and holding it set until the end of the cycle, the rearward edge of said lever presses against a pin 180 which is mounted in an arm 181 which forms the right hand end of a zero stop rocker frame 182 which bridges all of the numeral wheels 473 and is pivoted at each end of the carriage on the fixed studs 162. The lever 176 is pinned to the shaft 159 on the left hand end of which there is secured a duplicate lever which acts on a second pin 180 in the left hand arm 181, to provide for parallel operation of the zero stop rocker frame 182. This frame is provided with upstanding fingers 184 which normally stand out of the path of travel of the pins 481 of the numeral wheels (Figs. 2 and 5), but are moved into the path of these pins to arrest the wheels at zero as they are rotated in a subtractive direction in zero setting operations. Upon the completion of a cycle of operation of the shaft 153 and the cam 175 in a clockwise direction, the rocker frame 182 resumes its normal position under the influence of spring 178.

Rotation of shaft 153

The shaft 153 is adapted for selective rotation in either direction, according to the function it has to perform. In a commercial machine it should preferably be operated by motor power

under the control of selectively operable function keys, but such a driving means forms no part of the present invention and is not shown. This shaft could be driven selectively in either direction by a hand crank applied to its right hand end. A spring impelled locating roller 165 (Fig. 5) rides a cam 186 secured to shaft 153 to facilitate the location of said shaft in full cycle position.

Elemental operations

Total taking and value transporting operations of the numeral wheels 473 through the differential actuator gearing 477 are facilitated by this invention, since the crawl transfer accumulator wheels may be zeroed simultaneously. Aside from this there are five different and useful operations which may be performed by the selective rotation of shaft 153, in some of which the keys 160 and 170 must also be used. These five operations are:

1. Clearing the grand total indicator.
2. Transporting values from the accumulator to the grand total indicator.
3. Transporting values from the grand total indicator to the accumulator.
4. Accumulating grand totals.
5. Clearing the accumulator.

Four elemental operative movements are involved in these five different operations, as follows:

- (a) Depression of the key 160.
- (b) One cycle of clockwise rotation of shaft 153.
- (c) One cycle of counter-clockwise rotation of shaft 153.
- (d) Operation of key 170.

Operation No. 1 is affected by movement (c) (rotating shaft 153 one revolution counter-clockwise). This rotates the gears 150 and the wheels 157 until the teeth 156 arrest the grand total indicator wheels with 0's showing through the windows in the carriage housing.

Operation No. 2 is effected by movement (a) (depression of key 160) and (b) (rotation of shaft 153 clockwise). This clears the accumulator, transporting the value it contained to the grand total indicating wheels 157 which should have stood at zero when operation No. 2 was started. At the end of this operation the gears 480 resume their engagement with the output gears 477 of the differential actuator mechanism, as previously explained.

Operation No. 3 is effected by movements (a), (c) and (d). The rotation of shaft 153 in a counter-clockwise direction in this operation clears the grand total indicating wheels 157, transporting the value to the accumulator 473 where it will be added to any previous value which may have been registered. If accumulator 473 previously registered a complementary (negative) value the effect will be subtractive. Operation of key 170 following the rotation of shaft 153 restores the gears 480 to their normal engagement with gears 477.

Operation No. 4 is effected by movements (a), (c) and (b). In movement (c) the indicating wheels 157 are cleared, transporting the value to the accumulator 473 where it is added to the newly registered total to accumulate a new grand total, which is then cleared from the accumulator 473 and transported to the grand

total indicating wheels in movement (b), at the end of which operation latch 169 is automatically released, permitting the gears 480 to resume their normal position in engagement with gears 477.

Operation No. 5 is effected by movements (a), (b) and (c). In movement (b) the accumulator 473 is cleared to zero, transporting the value to the grand total indicator 157 which, if constructed according to Fig. 4, must have stood at zero before this operation was started. At the end of movement (b) the gears 480 are automatically released from engagement with gears 150 so that in movement (c) the grand total indicator 157 is cleared to zero.

I claim:

1. In a register, a series of supporting frames provided each with a cylindrical bearing, an accumulator including a series of differentially driven pinions mounted on said bearings, tens transfer mechanism of the direct wheel to wheel type and including cylindrical elements mounted within said bearings, a sectional shaft comprising sections each supported within two adjacent cylindrical transfer elements, and a series of numeral wheels each individual to and mounted upon a section of said shaft.

2. In a register, a series of supporting frames, an accumulator including cylindrical elements rotatably mounted in said frames and having movement transmitting extensions, a sectional shaft comprising sections each supported within two adjacent cylindrical elements, a series of numeral wheels each individual to and mounted upon a section of said shaft, and means for maintaining the individual shaft sections against excessive endwise displacement.

3. In a register, the combination with a series of yieldably driven zero setting gears and drive means operable to impart a simultaneous driving impulse to the gears of said series; of a series of supporting frames provided each with a cylindrical bearing, an accumulator comprising orbital differential gearing including a series of input pinions mounted on said bearings and designed for driving connection with the zero setting gears, tens transfer input elements mounted within said bearings, and a series of output numeral wheels provided with zero stops, and cooperating stop means adjustable to active position by the drive means.

4. In a register, the combination with a series of yieldably driven zero setting gears and drive means operable to impart a simultaneous driving impulse to the gears of said series; of a series of supporting frames provided each with a cylindrical bearing, an accumulator comprising orbital differential gearing including a series of input pinions mounted on said bearings and designed for driving connection with the zero setting gears, tens transfer input cylindrical elements mounted within said bearings, a sectional shaft comprising sections each supported within two adjacent cylindrical transfer elements, and a series of output numeral wheels each individual to and mounted upon a section of said shaft and provided with zero stops, and cooperating stop means adjustable to active position by the drive means.

GEORGE C. CHASE.
